INDEX FRAME ASSEMBLY

James H. Rand, North Falmouth, Mass., assignor
to Philrand, Inc., North Falmouth, Mass., a
corporation of Massachusetts

Application August 22, 1934, Serial No. 740,954

8 Claims. (Cl. 129—34)

This invention relates to an improved index device and more particularly to an index frame, especially such a frame of the book type. Certain forms of index frames or panels are characterized by opposite recesses or channels receiving the supports for index sheets or elements which are arranged in overlapping relationship. The present invention affords an improved frame of this type which may be formed of sheet metal, 5 preferably with separate frame portions or leaves combined to afford a book assembly. This assembly may include leaves arranged to receive index material bordered by flanged or beaded edge portions of the corresponding leaf so that these edge portions meet substantially to enclose the index material when the book is closed. If desired, a plurality of book sections may be arranged in juxtaposition with adjoining leaves disposed back to back so that a series of leaves may be combined in a single assembly with certain leaf portions having index material on both sides thereof. The present invention affords an improved arrangement of the edges of the leaf elements or frame portions, providing a strong relatively deep 10 beaded edge portion which also affords a channel or guideway for the index holders. This invention also provides an improved hinge arrangement which permits firm and sturdy connection of the successive leaf sections and which allows successive book units to be secured to 15 each other so that a series of units may be arranged in a single assembly with the backs of adjoining leaves in direct engagement.

This invention furthermore provides a hinged 20 cover or retainer detachably received by the channel flanges at each side of each frame portion and having a flap or plate normally engaging the uppermost index sheet to hold the sheets in proper superposed, overlapping relationship. Preferably this cover or retaining member may 25 be held in frictional engagement with the flanges at the sides of the frame so that it may be adjustably positioned along these flanges. For this purpose a support of resilient metal may be connected to the cover plate, having split end portions frictionally engaging the opposite flanges of the frame. The support may also be provided 30 with means to engage the upper edge of the upper index sheet element to prevent the cover slipping over this element.

In the accompanying drawings:

Fig. 1 is a front elevation of an index frame assembly constructed in accordance with this invention, a portion of the outer leaf being re- 35 moved;

Fig. 2 is a broken side elevation of such an assembly;

Fig. 3 is a horizontal section indicated by line 3—3 of Fig. 2;

Fig. 4 is an elevational view of the upper part 5 of a book section with a portion of the retainer folded upwardly and broken away at the right-hand side of the figure and with certain parts removed;

Fig. 5 is an elevational view showing a corner 10 portion of the book in its open position and showing a retainer tilted to the position which it may occupy as it is being removed or inserted in the frame;

Fig. 6 is a horizontal section of a portion of 15 the frame and the retainer assembly;

Fig. 7 is a similar view showing the manner in which the index elements are mounted in the frame; and

Fig. 8 is a section on line 8—8 of Fig. 4.

Certain features of this invention are generally applicable to index panels or frames of the type which may be kept on a desk, inserted in a suitable rack or supported on a swinging or rotatable mounting, such a panel or frame being characterized by opposite flanges cooperating with the adjoining body portion of the panel in providing flanges engaging the ends of supports upon the index elements. These index elements may comprise one or more sheets secured to the 20 holder strips or bars, the ends of which project into and are received by the channels. More specifically the present invention affords index 25 panels or frames of this type which are connected by suitable hinge means to provide a book assembly in the form of two or more leaves. This book assembly may be of the type that is conveniently portable and may be carried about to suit individual business requirements, or it may be conveniently kept upon the desk of the user.

As shown in Figs. 1, 2 and 3, each book assembly 30 comprises a pair of frames or leaf elements 1, having body portions 2 of sheet metal provided with integral marginal beads 3. Each of these beads is provided by bending the sheet metal outwardly to provide a portion inclined at an obtuse angle to the body portion 2 and providing a curved portion 4 spaced from the portion 2, as well as by bending the metal inwardly from the portion 4 to provide a section 5 substantially perpendicular to the section 2, and finally by bending the metal at right angles to afford a flange 6 in 35 spaced parallelism to the edge of the body portion 2. Thus a strong reinforcing bead is provided upon each of the long vertical margins of 40

the frame element 1, and each flange 6 cooperates with the adjoining portion of the body portion 2 in providing a channel 7 to receive the ends of holders upon the index elements.

5 Hinges 12 connect the members 1 to each other. These hinges 12 are provided with knuckle portions 13 (Fig. 1) which may comprise elongate pintle pins 14 about which the metal from the opposite hinge portions or leaves is turned, thus 10 affording a hinge somewhat resembling a piano hinge. When the leaves or panel elements 1 are disposed in their ordinary closed positions, as shown in Figs. 1, 2 and 3, the curved portions 4 of beads 3 may be in close juxtaposition, thus 15 closing the edges of the assembly so that the index material is protected. In this position of the parts the hinge 12 has leaf portions or sections 15 disposed in planes at an obtuse angle to each other and has its pintle pin or rod 14 disposed 20 inwardly of the angle thus defined and adjoining the curved portions 4 of the marginal beads 3. The portions 15 have flanges 15^a extending upon opposite sides of the body portions 2 of the leaf sections and secured thereto by a 25 series of rivets 16. The inner extremities of flanges 15^a are slightly inturned as indicated at 15^b. The flanges 15^a and the rivets 16 which may have flat heads afford thin, relatively flat assemblies so that the thickness of the panel sections is not substantially increased thereby.

If desired, a series of the book assemblies may be connected to each other in the portion 1 in back-to-back relation to provide a plurality of these units in a single assembly. For this purpose, as shown in Figs. 1 and 3, the adjoining hinged margins of the leaves and the corresponding flanges 15^a may be secured to each other by rivets 16^a and the outer edges of the juxtaposed leaves may be secured to each other 40 by rivets 17 (see Fig. 4).

The beads 3 in effect afford flanges of appreciable depth so that the index sheets or elements may be received between these flanges without protruding substantially thereabove and so that the book may be fully closed despite a substantial amount of index material contained therein. This index material may be of various types, preferably being in the general form of index sheets 20 of paper (Fig. 5) with supports 21 having ends 45 22 received in frictional engagement with the flanges 6, i. e. within the channels 7. The supports or holders 21 are preferably so shaped that the upper edge of one index element 20 is disposed above the holder of the next element, thus providing an arrangement of superposed partially overlapping elements as shown in Fig. 8. If desired, the holders 21 may be of the type disclosed in my copending application Serial No. 667,810, filed Apr. 25, 1933, which has since matured into 50 60 Patent No. 2,065,738, dated Dec. 29, 1936.

In order to assure the proper retention of the index material in place it is desirable to provide a suitable cover or retainer 30. This retainer may include a swinging plate 31, preferably of 65 sheet metal, which is pivotally connected to a sheet metal support 32. The latter preferably is formed from a return bent piece of sheet metal with the return bent portion disposed at its lower edge and having one of its legs turned around a 70 pintle pin 39 to afford the hinge connection with the plate 31. The return bent portion of the member 32 is preferably cut away to provide slots 36, Figs. 6 and 8, the metal adjoining these slots being slightly flared to afford such an effective 75 width to the bent portion of the member 32, that

it will positively engage the edge of the uppermost index element 20. Thus any possibility of the curved sheet metal element slipping by the upper edge of an index sheet or its holder is avoided, and danger of wedging or jamming of these parts is 5 obviated. The ends of the element 32 are preferably split to provide slots 38 engaging the flanges 6, the member 32 being arranged so that its opposite legs engage these flanges with a frictional contact tending to hold the retainer 30 in the 10 desired adjusted position. When it is desired to remove the retainer from the flanges it can be tilted to substantially the position illustrated (Fig. 5). Obviously the plate 31 may be swung upwardly to the position shown at the right of 15 Fig. 4 to afford ready access to the index elements 20 as desired.

At the lower edge of each leaf 1 a suitable card 60 may have tabs received in the channels 7 and act as a stop engaging the support for the lower- 20 most index element. Thus the index elements are held in closely superposed partially overlapping relationship with the lower element engaging this card and with the upper element passing 25 downwardly by the retainer 30, the edges of the index sheets and the retainer being juxtaposed to the marginal beads 3 of the frame.

At the upper and lower edge of each panel assembly inturned ears 40 may be afforded above and below the ends of flanges 6 and flat, generally tubular elements 41, which may conveniently be formed of metal or transparent material such as celluloid, may have their ends engaging these ears 40. The tubular elements 41 may be bent or bowed and then removed from the ears. At the 35 upper ends of the leaves, they may be formed of celluloid and may support any suitable identifying slip 42. This arrangement and further developments thereof are more fully disclosed in my co-pending application Serial No. 740,953, filed Au- 40 gust 22, 1934. At the bottom of each of the panel elements, the card 60 (Fig. 1) may have a depending extension 61 disposed behind element 41 and lateral extensions 62 resting on this element.

It is evident that this invention affords an 45 unusually sturdy and simple index frame or panel and particularly a book assembly which may be formed of such panels, the formation of the beaded edges of the panels being particularly effective and advantageous when employed in such 50 an assembly to afford elongate stops to hold the body portions of the panels spaced when the book is closed and also providing tray-like recesses for the index material. The flanges 6, being disposed in closely spaced relation to the body portion 2 55 of each leaf 1, permit the edges of the cards or sheet elements 20 to be disposed in closely spaced relation to the body portion of each leaf, as illustrated, for example, in Fig. 7. If desired, frames of this general type may be provided in different 60 widths but with the flanges 6 thereof having edges spaced at a uniform standardized distance. Thus when relatively wide leaves were provided, the flanges 6 would be relatively wide, with their edges spaced at the same distance from each 65 other as the edges of narrower flanges provided on a narrower leaf. This arrangement permits the employment of holders 21 of standardized dimensions for index frames and leaves having a variety of widths. The hinge arrangement provided by this invention not only permits the complete enclosing of the edges of the material, but also avoids objectionable projections which are likely to catch upon or scratch surrounding objects or the hands of a user of the index. These 70 75 80 85 90 95 98 99 100

hinges are furthermore advantageous in permitting the assembly of a plurality of book sections in superposed relation, as may be desired. The arrangement of the flanges which retain the index sheets or holders in place also cooperates with the retainer which may be readily removed, if desired, to facilitate more convenient handling, insertion of or removal of the index sheets or elements.

10 I claim:

1. An index frame comprising a body portion of sheet metal, and marginal flanges upon opposite edges of said body portion, each flange including an outer wall at an obtuse angle to the body portion, a curved bead portion in spaced relation to the plane of the body portion, an inner wall extending inwardly substantially perpendicular to said body portion, and an extension of said inner wall disposed substantially at right angles thereto and in parallel juxtaposition to the body portion, said inner wall and its extension meeting at a corner which is juxtaposed to the outer wall adjoining the body portion.

2. The combination comprising an index frame having opposite substantially coplanar flanges to receive index material, and a support formed of return bent sheet material having slits at its ends so that faces of opposite sheet portions frictionally engage opposite faces of the flanges.

3. The combination comprising an index frame having oppositely disposed, inwardly extending flanges to receive index material, and a retainer including a support formed of sheet material bent back upon itself and a plate pivotally connected to said support, the ends of the support being provided with slits so that the opposite portions of the retainer engage opposite faces of the flanges.

4. An index assembly comprising an index frame having oppositely disposed, inwardly extending flanges to receive index material, and a retainer part formed of sheet material bent back upon itself, the ends of the part being provided with slits so that the opposite portions of the retainer engage opposite faces of the flanges, the return bent portion of said retainer being provided with cut-away flared openings to engage the upper edge of an index sheet or the like.

5. An index assembly comprising an index frame having oppositely disposed, inwardly extending flanges to receive index material, and a retainer including a support formed of sheet material bent back upon itself, and a plate pivotally connected to said support, said bent portion of said retainer being provided with cut-away flared

openings to engage the upper edge of an index sheet or the like.

6. An index frame assembly of the book type comprising a series of leaves of sheet material, each of said leaves having opposite beaded marginal flanges formed by bending the wall outwardly and over, a portion of the inner wall of each of said flanges being extended to provide a retaining flange in parallel relation to the general plane of the leaf, each of said retaining flanges terminating in spaced relation to the upper edge of a leaf, the beaded flange being extended above said retaining flange and provided with an ear, and a flattened tubular element of distortable material disposed with its ends engaging said ears.

7. An index assembly comprising a frame having a flat body portion and retaining flanges extending along opposite edges of the body portion in spaced relation thereto to cooperate therewith in affording channels, a plurality of index elements having supports received in said channels and sheets extending from the supports and arranged in overlapping relationship, the frame having ears disposed adjacent its lower edge and below the retaining flanges, a supporting element having its ends supported by said ears, and a sheet member having a depending extension disposed between said supporting element and the body portion of the frame, having lateral extensions resting upon said element, and ears disposed within the channels, the upper edge of said sheet member acting as a stop to engage the support of the lowermost index element.

8. An index frame comprising a plurality of similar book assemblies, each having a pair of similar leaves, each leaf being a planar body portion, and opposite flanges cooperating with the body portion in providing a channel to receive index material, the leaves of each assembly being interconnected by a hinge including complementary hinge portions, each rigidly fixed to the corresponding leaf, a single common pintle engaged by barrel sections of the hinge portions, and fastening elements rigidly securing the hinge portions to the corresponding leaves, one leaf of each assembly having its body portion secured in back to back relation to a leaf of an adjoining assembly, certain of said fastening elements also connecting the leaves that are arranged in back to back relation, whereby a frame of any desired even number of leaves may be built up from similar book assemblies consisting of similar leaves and similar hinges.

JAMES H. RAND.
